UNITED STATES PATENT OFFICE.

ELMINA R. SLEEPER, OF SOUTH ORANGE, NEW JERSEY.

NURSERY-CHAIR.

SPECIFICATION forming part of Letters Patent No. 588,707, dated August 24, 1897.

Application filed December 20, 1895. Renewed July 15, 1897. Serial No. 644,729. (No model.)

To all whom it may concern:

Be it known that I, ELMINA R. SLEEPER, a citizen of the United States, and a resident of South Orange, in the county of Essex and State 5 of New Jersey, have invented certain new and useful Improvements in Nursery-Chairs, of which the following is a specification.

My invention relates to nursery-chairs; and it consists in certain novel parts and combinations of parts particularly pointed out in 10 the claims concluding this specification.

In the accompanying drawings I have shown my invention embodied in the form which is at present preferred by me; but it will be 15 understood that various modifications and changes may be made in the construction without departing from the spirit of my invention and without exceeding the scope of my claims.

20 Referring to the drawings, Figure 1 is a longitudinal section through a nursery-chair with my invention applied thereto. Fig. 2 is a front detail view of the urinal-tube shown in Fig. 1. Fig. 3 is a top view of the same on 25 an enlarged scale.

The following is a description of the accompanying drawings:

1 is a nursery-chair of ordinary construction. On the front part of the cut-away seat 30 is attached a urinal-tube 4, made of flexible material—such, for example, as vulcanized soft rubber—in whole or in part. At the upper end this tube is preferably enlarged and curved, as at 5. As shown, the tube, at its 35 upper end, is provided with an inwardly-projecting hood, which extends above the surface of the seat and over the opening therein.

6 is a clip or other suitable contrivance attached to the chair in any convenient man-

ner—as, for example, by screws shown—by 40 which the tube 4 5 is removably attached to the chair, permitting said tube to be rotated in the clip, as well as to be removed for renewal or cleansing.

The object of the device is to prevent male 45 infants soiling their clothing or the chair.

The device is readily attached to any ordinary nursery-chair by cutting a **U**-shaped notch in the front part of the seat, of size large enough to admit the clip or loop of wire 50 which serves as a holder. The tube being inserted in this, the device is ready for use. Before seating the infant the tube should be reversed, so that the mouth part shall be turned outward, which leaves the opening in 55 the chair unobstructed. After the infant is seated the tube should be turned back again to the position shown in the drawings and the mouth part properly adjusted to serve the purposes for which the contrivance is de- 60 signed.

What I claim is—

1. The combination with a nursery-chair of a urinal-tube extending above the seat of the chair provided with a hood projecting over 65 the opening in the chair, said tube being reversible, so as to leave said opening unobstructed, substantially as described.

2. The combination with a nursery-chair of a urinal-tube attached thereto extending 70 above the seat of, and over the opening in the chair, provided with a hood projecting inwardly over and beyond the opposite portion of the tube.

ELMINA R. SLEEPER.
